UNITED STATES PATENT OFFICE.

JOHN H. CUNTZ, OF HOBOKEN, NEW JERSEY.

TELEPHONE AND TELEGRAPH RELAY OR REPEATER.

1,215,348.

Specification of Letters Patent.

Patented Feb. 13, 1917.

Original application filed February 19, 1903, Serial No. 144,134. Divided and this application filed August 10, 1912. Serial No. 714,337.

To all whom it may concern:

Be it known that I, JOHN H. CUNTZ, a citizen of the United States, and resident of Hoboken, in the county of Hudson and State of New Jersey, have invented certain new and useful Improvements in Telephone and Telegraph Relays or Repeaters, of which the following is a specification, reference being had to the accompanying drawings, forming a part hereof, this being a divisional case of my application Serial No. 144,134, filed February 19, 1903.

This invention relates to means for relaying or repeating telephone and telegraph messages. Telephone repeating coils have been used in which there are two windings, a primary and a secondary, variations in the current through one inducing a varying current in the other. But although such coils are of service for certain purposes in telephone work, they have not been found helpful in extending the distance over which telephonic speech may be transmitted.

In my relay, or repeater, in addition to the primary and secondary coils, connected, respectively, to the incoming and outgoing line circuits, I use another coil insulated from the two former and in circuit with an independent source of current.

In one form of this relay the coils are wound around an iron core and a continuous current is passed through the third, or auxiliary coil, of such a strength that the magnetic field due to it will cause the iron of the core to be at, or about, the point of maximum permeability. It is well known that the permeability of iron varies with the strength of the magnetic field in which it is placed. At low magnetizations, such as are caused by telephonic and submarine telegraphic currents, the permeability is comparatively low. It (the permeability) increases with increasing magnetization up to a point where the strength of the field is about from 1 to 10 C. G. S. units, varying, of course, with different kinds of iron. After passing this point, the permeability again decreases. The iron when at and near the maximum permeability point is in a state where small variations in the current of the primary coil will cause comparatively great changes to occur in the iron of the core, and, hence, in the induced currents of the secondary coil. The variations of the current in the secondary coil and in the line cir-

cuit to which it is connected, will then be equal to those of the primary coil in number, and similar in form, but will have a greater amplitude or intensity, and thus the message will be carried on with increased strength.

When an alternating current is passed through the auxiliary coil, the magnetic particles of the core will be kept in continual motion, and will then be in a particularly sensitive condition, so that any variations in the primary current will cause comparatively great changes in the magnetic state of the core, which changes will induce corresponding variations in the current of the secondary coil, and of the line circuit to which it is connected. For telephone purposes this alternating current should be of a frequency below the limit of audibility, and should have a smooth wave form, without angles or sudden changes and breaks which would cause sounds in the telephone. And whenever the alternating current is used for the purposes here indicated, it should preferably have a very low frequency, just great enough to keep the magnetic particles of the iron in motion, and not so high as to cause any deleterious effects. This slowly alternating current in the auxiliary coil will, of course, induce corresponding currents in the "primary" and "secondary" coils and hence in the line wires, but these currents will not produce hurtful effects if the frequency is low enough. There will be on the line an alternating current having a very long period and smooth wave form, on which will be superposed the telephonic and telegraphic currents like little ripples on an ocean ground swell, as indicated in Figure 7.

For some purposes I prefer to have the alternating current of a mean strength such as will produce a magnetic field which causes the average state of the iron to be at or near that of maximum permeability.

In certain cases it is advantageous for the iron core to form a closed magnetic circuit, and I then make my iron core in the shape of a ring or in some other suitable form. The core is composed preferably of fine wires of iron possessing high permeability and a low hysteresis coefficient.

When the coils are used without an iron core, the variations in the primary current induce currents in the auxiliary coil which are superposed upon the normal current,

either continuous or alternating, passing through the auxiliary coil. The so-varying auxiliary current will then induce currents in the secondary coil, which will have a 5 greater intensity than those in the primary coil, although similar in form.

Besides being of service in telephone work, my relay or repeater is adapted to telegraph work, and, particularly, to submarine telegraphy, where the currents are very feeble.

My relay or repeater will transmit messages in either direction equally well, and the "primary" coil can act as a "secondary" coil, and the "secondary" coil as a "primary," with equal facility. The names "primary" and "secondary" are used in these specifications for the sake of clearness.

In the accompanying drawings:

Fig. 1 represents a relay or repeater with 20 a ring-shaped iron core, about which are wound a primary coil, connected to the incoming line wires, a secondary coil, connected to the outgoing line wires, and an auxiliary coil connected to an independent 25 source of alternating current.

Fig. 2 represents a relay or repeater with a ring-shaped iron core, the primary and secondary coils being as in Fig. 1, but the auxiliary coil being here connected to an independent source of continuous current.

Fig. 3 represents a relay or repeater with a straight iron core, the primary, secondary and auxiliary coils being connected as in Fig. 1, the auxiliary coil, as shown, being in 35 circuit with an independent source of alternating current.

Fig. 4 represents a relay or repeater in which the primary and secondary coils are wound on separate iron cores, the auxiliary 40 coil being in two parts, one wound on the same core with the primary coil, the other part wound on the same core with the secondary coil. The auxiliary coil, as shown, is in circuit with an independent source of 45 continuous current, but it may also be in circuit with a source of alternating current.

Fig. 5 represents a relay or repeater in which the coils are arranged and connected as in Fig. 4, but in which there are no iron 50 cores.

Fig. 6 represents a relay or repeater in a telegraphic system such as may be used in submarine work.

Fig. 7 is a curve representing an alternating current wave of very long period, or low frequency, with shorter current waves, of higher frequency, such as occur in telephone and telegraph work, superposed upon it.

In Fig. 1, M is an iron or steel ring composed, preferably, of thin, iron wires, on which are wound: a primary coil, P, in circuit with the line wires, t, t , and the telephone transmitter, T; a secondary coil, S, 65 in circuit with the line wires, r, r , and the

telephone receiver, R; and the auxiliary coil, Q, in circuit with the source of alternating current, G.

In Fig. 2, M is an iron or steel ring composed, preferably, of thin iron wires, on 70 which are wound: a primary coil, P, in circuit with the line wires t, t , and the telephone transmitter, T; a secondary coil, S, in circuit with the line wires r, r , and the telephone receiver, R; and the auxiliary coil, 75 Q, in circuit with the source of continuous current, H.

In Fig. 3, M_3 is an iron or steel straight core composed, preferably, of thin iron wires, on which are wound: a primary coil, 80 P, in circuit with the line wires, t, t , and the telephone transmitter, T; a secondary coil, S, in circuit with the line wires, r, r , and the telephone receiver, R; and the auxiliary coil, Q, in circuit with the source of alternating 85 current, G.

In Fig. 4, M_1 is an iron or steel core which is here shown straight, but may also be of any other shape, and which is composed, 90 preferably, of thin iron wires, on which are wound: a primary coil, P, in circuit with the line wires, t, t , and the telephone transmitter, T; and an auxiliary coil, Q_2 , in circuit with another auxiliary coil, Q_2 , and a source of continuous current, H. M_2 is an iron or steel core which is here shown straight, but may also be of any other shape, 95 and which is composed, preferably, of thin iron wires, on which are wound: a secondary coil, S, in circuit with the line wires, r, r , and the telephone receiver, R; and an auxiliary coil, Q_2 , in circuit with a source of current, H, which is here shown as continuous, but may also be alternating.

In Fig. 5, P is a primary coil, without any 105 iron or steel core, in circuit with the line wires, t, t , and the telephone transmitter, T. Q_1 is an auxiliary coil, insulated from P, but in close proximity thereto, or wound about it, and in circuit with another auxiliary coil, Q_2 , and a source of current, H. S is a secondary coil, also without any iron or steel core, in circuit with the line wires, r, r , and the telephone receiver, R. Q_2 is an auxiliary coil, insulated from S, but in 110 close proximity thereto, or wound about it, in circuit with a source of current, H, which is here shown as continuous, but may also be alternating.

In Fig. 6, M is a core of iron or steel, but 115 preferably composed of thin iron wires, on which are wound: a primary coil, P, in circuit with the line wire, k , and the telegraphic transmitting apparatus, K, the circuit being completed through the earth connections E_1 and E_2 ; a secondary coil, S, in circuit with the line wire, l , and the telegraphic receiving apparatus, L, the circuit being completed through the earth connections E_3 and E_4 ; and an auxiliary coil, Q, 120

125

130

in circuit with a source of alternating current G.

In Fig. 7, A, A, A is a curve representing an alternating current wave of a very long period, on which are superposed high-frequency telephonic or telegraphic currents, shown at a, b and c.

All of the coils, P, S and Q, mentioned in these specifications, are insulated from the iron core, from each other and between their own turns.

In all the figures, the "primary" coil, P, will act as a secondary coil, and the "secondary" coil, S, will act as a primary coil when the direction of transmission is reversed, and will act thus equally well as before; they have been shown in the figures as designated for the sake of clearness. Also, for the sake of clearness, the coils have been shown, in all the figures, as occupying separate portions of the core, but they may equally well be wound over each other in layers, properly insulated from each other, and may be in two or more sections, properly connected.

For transmitting in both directions, the number of turns of the "primary" and "secondary" coils are preferably equal. When continuous current is used in the auxiliary coil, the strength of the current and the number of turns of the coil should be so proportioned, that a magnetic field will be created of an intensity such that the iron of the core will be at or about its state of maximum permeability.

When an alternating current is used, the

frequency should preferably be very low, and for telephonic purposes must be below the limits of audibility.

In general, the figures are diagrammatic, and show the objects described in conventional form, and I do not confine myself to the exact constructions here indicated, but what I here claim as my invention and desire to secure by Letters Patent is:

1. A relay or repeater, including a plurality of auxiliary coils, through which is flowing current from an independent source, and coils in circuit with the line wires and in inductive relation to the auxiliary coils.

2. A relay or repeater, including an independent source of direct current, a plurality of iron cores, a plurality of auxiliary coils one on each core, through which flows a direct current from said source, and a plurality of coils in circuit with the line wires each in inductive relation to one of the auxiliary coils and to the iron cores.

3. A relay or repeater, including a plurality of auxiliary coils, through which is flowing direct current from an independent source, and coils in circuit with the line wires and in inductive relation to the auxiliary coils.

In testimony whereof, I have signed my name to this specification, in the presence of two subscribing witnesses, this 8th day of August, 1912.

JOHN H. CUNTZ.
